UNITED STATES PATENT OFFICE.

JOHN C. HENRY, OF KANSAS CITY, MISSOURI.

COMBINED FIRE AND POLICE ALARM.

SPECIFICATION forming part of Letters Patent No. 295,249, dated March 18, 1884.

Application filed August 30, 1883. (No model.)

To all whom it may concern:

Be it known that I, JOHN C. HENRY, a citizen of the United States, residing at Kansas City, in the county of Jackson and State of Missouri, have invented certain new and useful Improvements in a Combined Fire and Police Alarm, of which the following is a specification.

My invention has for its object to provide a signal-box which shall require a minimum of intelligence in the person sending the message, and enable the transmission from the same box, and by the employment of the same automatic make-and-break device, of at least two distinct calls or signals, one of which may be the signal for fire and the other police. To this end I provide a signal-box with a hinged door on each side, each of which doors is connected by a suitable rod or lever with a weight or spring of a clock mechanism in such manner that by the opening of either door the weight will be raised or the spring wound, (as the case may be,) in readiness to actuate the make-and-break mechanism when permitted to do so by the closure of the door. The door for sending either the fire or police call is provided with a separate make and break for sending one or any number of impulses of current to line to effect a shifting of the dial of the indicator at the central station, one or any number of spaces additional to those affected by the main make and break which alone is operated by the other door. The actuating-weight being raised to potential position by the opening of one of the doors, it is there held until by the closure of such door a catch is released, allowing the weight to descend to operate the make-and-break device.

In order that my invention may be more fully understood, I will proceed to describe it with reference to the accompanying drawings, in which—

Figure 1 is a vertical sectional view of the signal-box. Fig. 2 is a horizontal sectional view thereof, taken on the line 22, Fig. 1. Fig. 3 is a vertical sectional view taken at right angles to Fig. 1. Fig. 4 is a face view of the indicator, part of the dial being broken away to show the interior mechanism.

1 is the box or casing containing improved signal apparatus, having suitable means, 2, (which may be either an aperture or binding-post,) for the passage of the electric conduct-

or. Each side of the box is provided with a door, 3 3', hinged at its upper end to the box, and provided at such upper end with a ratchet- 55 segment, 4 4', adapted to engage a gravity or spring catch, 5 5', and thus prevent the closure of the door, when once opened, until it has been lifted to its extreme position and the catch is allowed to fall back to vertical position at the 60 end of the ratchet. The rattling noise made by the pawl or ratchet 4 5 will also serve as an alarm to those in the neighborhood, notifying them of tampering with the box.

Pivoted at 6 6' to the segments 4 4' are connecting-rods 7 7', slotted at their inner ends for the reception of the pins 8 8', on the upper and lower ends, respectively, of the rocking lever 9, which is pivoted at 10 to the side of the casing. The weighted lever 11 is hung 70 from pivot 12, and adapted to be operated by rocking lever 9 through the medium of connecting-rod 13, pivoted at one end to the pin 8' of said lever. The weight 14 is adjustable, to regulate the leverage of the arm 11. Said 75 arm bears a pivoted dog, 15, held by spring against the toothed wheel 16—the first of a train of gears adapted to transmit motion to the make-and-break mechanism. It will now be seen that as either door 3 3' is unlocked 80 and opened to the position shown in the dotted lines, Fig. 1, the weighted arm 11 will be gradually lifted until the door has reached its highest point, the pawl 15 meanwhile slipping loosely over the teeth of the wheel 16. 85 The weight now stands ready to fall and drive the train for actuating the make-and-break device. The shifting of the rod 7 by the closure of the door will not disturb the weighted arm 11, as the slotted arms 7 7' will ride over 90 the pins 8 8' without disturbing the lever 9. The release of the train is, however, effected by the following means: The notched wheel 17, adapted to be driven by the weighted arm 11, through the train of gears 16 18 19, is provided with a pin or stop, 20, adapted to bear, for stopping the train, against a lug, 21, on upright rod 22. The rod 22 is allowed slight rotary movement in the straps 23, which support it from the frame 24, in which the wheels 95 of the train find bearing. A spiral spring, 25, fixed at its ends to one of the brackets 23, and to the rod 22, respectively, serves to return the rod 22 and its lug 21 to its normal 100

position of engagement with the pin 20. The lower end of rod 22 is flattened into the form of a plate, 26. Sliding rods 27 27' have bearing in supports 28 29, fixed to the base of the 5 casing. Surrounding the rods 27 27' are spiral springs 30, having abutment against the supports 29, and serving, by bearing against the fixed collars 31 on the rods 27 27', to constantly force said rods outward against the doors 3 3'. 10 The inner ends of the rods 27 27' are formed with cut-away portions 32, to receive the plate 26, permitting the free movement of said plate independently of either rod when being operated by the other rod. By affording the 15 spring-staff 22 slight freedom of rotary movement in either direction, under the control of spring 25, the head 33 of either rod 27 27' is allowed to slip past the plate on the opening of either door 3, the plate being only slightly 20 deflected and the lug 21 turned in toward the notched wheel 17 without releasing the stop 20 of said wheel. The plate 26 springs immediately back to place on the passage of the head, in readiness to engage such head when 25 the rod 27 or 27' is again pressed in by the closure of the door. The plate 26 and rod 22 are thus on the closing of the door given a slight rotation, the lug 21 thus disengaged from the pin 20, and the weighted arm 11 allowed 30 to fall, driving the train 16 18 19, and rotating the notched wheel 17 until by the springing back of catch 22 21 its motion is arrested.

A binding-post, 34, has electrical connection, by means of wire 35, with the indicator at the 35 station, and also with a flat spring, 36, of sufficient length to be engaged and vibrated by the teeth of wheel 17. The end of the spring 36 bears a vertical rod or plunger, 37, working in cup 38, which is partially filled with 40 mercury covered with glycerine, and which has electrical connection, as shown, with ground-plate 39. It will now be seen that by the rotation of the wheel 17 the plunger 37, being reciprocated vertically, will alternately 45 make and break contact with the mercury of cup 38, and thus cause similar interruptions of the current on the line operating the arrow 50 of indicator 51, in the usual manner.

It will be seen that with mechanism such as 50 above described the same number of interruptions of current, and consequently the same indications on the dial, will be effected by the opening or closing of either door.

In order to provide for the sending of different calls from each door, I make a branch from the line-wire at 40 by means of spring-conductor 41, said spring being held up in the closed position of the door by segment-arm 4; but which, when the door is being opened, 60 falls on contact-piece 42, connected to the ground-wire, thus making the circuit and allowing the passage of a continuous current on the line and moving the indicator-arrow forward one space. When the door is closed, the 65 contact 41 42 is broken before the release of the train.

It is obvious that instead of the arrangement described for sending one additional impulse to line any ordinary make and break operated by the door 3 for interrupting the current any desired number of times may be employed. The supplemental make and break is preferably arranged to be operated by the fire-door. In such a case, there being an even 70 number of teeth on the wheel 17, even numbers on the dial would be a call for police, and odd numbers indicate fire, the additional stroke for the odd numbers being always obtained by the make and break operated by the door. The continued current obtained by this supplemental device also enables the insertion (preferably in a local or branch circuit, as shown) of an alarm-bell, 43, which will give a prolonged alarm only to indicate fire. 75

For easy reading of the indicator-dial, the 80 odd and even numbers may be arranged, as shown, in separate concentric circles.

Additional gears 44 45 46 may be added to the train to drive a rotary vane, 47, for moderating the speed thereof.

For some purposes levers may be substituted for the doors 3 3', the remaining parts of the invention being in such case adapted to operate in a substantially similar manner.

At 48 is shown the battery or generator, and 90 at 49 the necessary ground-connections.

Whatever novel subject-matter I have shown and described but not claimed herein is reserved for claiming in future applications.

I am aware that it has been before proposed 100 to set the alarm of a fire-telegraph by means of a swinging door connected with the winding mechanism. This, therefore, I do not broadly claim.

Having thus described my invention, the 105 following is what I claim as new therein and desire to secure by Letters Patent:

1. In a signal-box having suitable line and ground connections, and with a make-and-break device for giving the prescribed call 110 from said box, a supplemental make and break for giving signals additional to the main call, and duplicate mechanism, both adapted to operate the main circuit-breaker, and one the supplemental circuit-breaker in addition, as 115 set forth.

2. In a signaling apparatus, the combination, with a signal-box having means of sending, in addition to the regular call, a preliminary or subsequent impulse of some duration, 120 the indicator, and alarm, the latter being adapted to be operated only by the supplemental call, as set forth.

3. An electric signal-box provided with two independently-hinged doors or levers, each 125 connected with and adapted to operate the regular call through the medium of intermediate mechanism, and one of said doors or levers having a separate make-and-break device for sending additional impulse or impulses to line, substantially as set forth.

4. In a signal-box, the combination, with a

weighted arm or spring and a train adapted to be driven thereby to transmit the call, of two independently-movable levers or doors, so connected with such weighted arm or spring as by being lifted to set the same in position for driving the train, substantially as set forth.

5. The combination of door or doors having means of connection to the call mechanism, with segment rack or racks fixed to such door or doors, and pawl or pawls adapted to engage with such segment-racks until the door has reached its extreme position, substantially as set forth.

6. The combination, with one or more doors or levers, 3 3', of slotted connecting-rods 7 7', rocking lever 9, connecting-rod 13, and weighted arm 11, substantially as and for the purpose set forth.

7. In combination with door or doors 3 3', the train 16 18 19, and weighted arm 11, adapted to drive such train when set by the opening of one or other of the doors, and the stop mechanism adapted to be moved by the closure of such door, and thus release the train, for the purpose set forth.

8. In combination with a make-and-break wheel having suitable means for rotating the same, and stop or pin 20, the spring-rod 22, having stop-lug 21 and plate or arm 26, and the spring rod or rods 27, adapted to release the stop mechanism when the door is closed, substantially as set forth.
